OTHER PUBLICATIONS

Gadgedsgo, "The Amazing Football Candle," <http://gadgetsogo.com/Amazing-Candle-football-party-NFL-college-gameday-fireworks-parties.html>, Sep. 2, 2015, 2 pages.*Primary Examiner* — Elizabeth J Oswecki(74) *Attorney, Agent, or Firm* — Slater Matsil, LLP(57) **CLAIM**

The ornamental design for a football trophy candle, as shown and described.

DESCRIPTION

FIG. 1 is a top, front, right side perspective view of a first embodiment of a football trophy candle, showing my new design in an open position;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, right side perspective view of a second embodiment of a football trophy candle, showing my new design in an open position;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken-line disclosure of elements is understood to represent portions of the article in which the design is embodied, but which form no part of the claimed design.
